DESIGN FOR AN ELECTRIC FENCE INSULATOR

Ralph R. Smith, Lakewood, Ohio

Application December 18, 1939, Serial No. 88,995

Term of patent 14 years

To all whom it may concern:

Be it known that I, Ralph R. Smith, a citizen of the United States, residing at Lakewood, in the county of Cuyahoga and State of Ohio, have invented a new, original, and ornamental Design for Electric Fence Insulators, of which the following is a specification, reference being had to the accompanying drawing, forming part thereof.

Fig. 1 is a perspective view of an electric fence insulator, showing my new design;

Fig. 2 is a side elevational view and

Fig. 3 is a plan view of the same.

I claim:

The ornamental design for an electric fence insulator, as shown.

RALPH R. SMITH.
